UNITED STATES PATENT OFFICE.

HARRY A. JACKSON, OF SEARSBOROUGH, IOWA.

DESIGN FOR A RIBBON-CLASP.

SPECIFICATION forming part of Design No. 29,063, dated July 19, 1898.

Application filed June 25, 1898. Serial No. 684,508. Term of patent 7 years.

To all whom it may concern:

Be it known that I, HARRY A. JACKSON, a citizen of the United States, residing at Searsborough, in the county of Poweshiek and State 5 of Iowa, have invented and produced a new and original Design for a Ribbon-Clasp; and I do hereby declare the following to be a full, clear, and exact description of the same, reference being had to the accompanying drawings, forming a part thereof.

My invention relates to the unitary design for a ribbon-clasp, as shown in the accompanying drawings, in which—

Figure 1 is a perspective view of a ribbon-clasp embodying the design. Fig. 2 is a top plan view of the same. Fig. 3 is a side elevational view.

A in the drawings designates the clasp, which consists of a single piece of spring-wire 15 formed at its opposite ends into coils B, connected by a main stem or cross-bar C. This cross-bar is straight throughout its entire 20 length and is arranged just forwardly of the

center of each coil, the latter being formed by the curvature of the wire at right angles there- 25 to into the shape of an open ring, the free end *d* of which lies beneath and immediately in rear of said cross-bar. The wire is then bent at right angles and extended downward to form a straight vertical shank *e*, which is 30 disposed at the center of the coil and provided at its lower end with a short inwardly-projecting horizontal arm *f*, the two arms of the shanks being arranged in alinement, as shown.

Having thus described my invention, I 35 claim—

The design for a ribbon-clasp, as herein shown and described.

In testimony whereof I affix my signature 40 in presence of two witnesses.

HARRY A. JACKSON.
